UNITED STATES PATENT OFFICE.

HERBERT WATSON HOWELL, OF WINNIPEG, MANITOBA, CANADA.

COMBINATION BENCH AND FOLDING COT.

1,176,963.

Specification of Letters Patent. Patented Mar. 28, 1916.

Application filed February 9, 1915. Serial No. 7,115.

To all whom it may concern:

Be it known that I, HERBERT WATSON HOWELL, of the city of Winnipeg, in the Province of Manitoba, Canada, have invented certain new and useful Improvements in Combination Benches and Folding Cots, of which the following is the specification.

The invention relates to household furniture and more particularly to a combination bench and folding cot and the object of the invention is to provide a combined article of furniture the construction of which is such that it may be readily extended to form a cot and is readily folded to convert it into a bench.

A further object of the invention is to provide an article of furniture of simple and durable construction the arrangement of the parts of which is such that the device may be completely folded for transportation or storage.

A still further object of the invention is to construct the combination bench and cot so that a storage compartment is formed therein in the folded position, such compartment being useful for receiving the customary bed clothing.

With the above objects in view the invention consists essentially in the arrangement and construction of parts hereinafter more particularly described and later pointed out in the appended claims, reference being had to the accompanying drawings in which:

Figure 1 represents a side view of the combination article as it appears when folded or closed to form a bench. Fig. 2 represents a front view of the article as it appears in Fig. 1. Fig. 3 represents a plan view of the article as it appears when extended to form a cot. Fig. 4 represents a longitudinal sectional view centrally through the cot. Fig. 5 is an enlarged vertical sectional view through the article when folded. Fig. 6 represents an enlarged detailed vertical sectional view through the joint formed between the lazy tong levers.

In the drawings like characters of reference indicate corresponding parts in each figure.

1 and 2 are sets of lazy tongs, each set being formed from similar pairs of intersecting equal length levers 3 and 4 pivotally connected centrally by bolts 5 and having the upper end of adjacent pairs of levers fastened together pivotally by bolts 6 and the lower ends of the adjacent levers crossed and

also pivotally connected together by bolts 7. It will be noticed that all of these bolts are fitted with screw heads so that they can be sufficiently tightened by means of a screw driver. The inner ends are supplied with nuts. Washers 7' are supplied on the bolts between the levers of the lazy tongs to allow of free movement. The opposing inner levers of the sets of tongs are connected by equal length cross bars 8, the cross bars being fastened to the levers by wood screws 9 and being located adjacent the lower joints formed between the levers.

10 and 11 are angularly disposed brace bars having their opposite ends secured to the cross bars and to the inner levers of the lazy tongs.

12 is a terminal transverse head strip permanently secured to opposing levers at one end of the combination bench and cot and 13 is a transverse terminal closure foot board secured to opposing lazy tongs at the opposite end of the combination bench and cot.

14 is a heavy canvas or similar flexible top piece having the sides thereof fastened to the lazy tongs by means of upper wood screws 14' and the ends thereof fastened to the transverse head and foot boards by means of wood screws 15 and 16 supplied with suitable washers 17. Reinforcing cross bands 14² are sewn at suitable intervals to the under side of the top piece and have their ends turned over the edges of the top piece and sewn down to the same. The wood screws 14' pass through the bands and washers 14² are supplied on the wood screws and bear against the bands.

18 is a cover fastened by means of hinges 19 to the head strip 12 and forming the bench seat when the tongs are closed in. The cover is supplied with side strips 20 and 21 and with a front cross strip 22, the side strips appearing to the sides of the lazy tongs when folded, while the front strip closes over the foot board and holds the tongs against spreading after the cover has been closed down.

23 is a hook secured to the foot board 13 and 24 is an eye screwed into the under side of the strip 22. The hook is designed to be engaged with the eye as shown in Fig. 2 when the tongs are folded in.

25 and 26 are a pair of flexible straps having their ends connected with the lazy tongs and with the cover, these straps being arranged to prevent the cover falling too far

2
back when the same is thrown up to the position shown in Fig. 4.

27 is a gate secured by spring hinges 28 to the cross bar 8 passing between the terminal pair of levers at the head end of the cot. This gate is arranged, in the folded position of the article, to close in against the inner pair of terminal head levers as shown in Fig. 5 and to take the position in 10 the extended cot, such that the upper edge thereof engages with the lower edge of the cover 18 or as shown in Fig. 4 of the drawings. A pivoted cleat 29 is secured to the terminal head strip 12 and is arranged to 15 hold the gate closed in the folded position of the cot.

In referring to Fig. 5 it will be seen that 20 a storage compartment 30 is formed in the folded article, in which material, such as bedding can be placed, entrance being had to the storage compartment through the gate. This storage compartment is closed 25 in at the top by the canvas, at the front by the terminal foot board and at the bottom by the cross bars.

It will be seen from observing Figs. 1 and 30 2 that when the tongs are folded and the cover closed down a very compact bench is provided. In the folded position it is impossible for the levers to spread as the foot board is caught behind the strip 22. The hook and eye prevent the bench cover 18 from being accidentally raised.

When it is desired to use the device as a 35 cot it is only necessary to release the hook, throw up the bench cover, release the gate and pull out the tongs as far as permitted by the flexible top 14. One can then recline on the cot so formed and the bench cover can be used as a holder for a pillow.

I wish to point out that by crossing the 40 lower ends of the levers forming the lazy tongs, I provide a very substantial cot as there is an increased spreading action given 45 the tongs by this construction, which results in the maintaining of a particularly taut top when one is resting on the cot.

What I claim as my invention is;—

1. A combination bench and folding cot

Copies of this patent may be obtained for five cents each, by addressing the "Commissioner of Patents, Washington, D. C."

comprising, lazy tong side members formed 50 from intersecting pairs of inner and outer levers pivotally connected together, suitably braced cross bars connecting opposing inner levers, said cross bars being located adjacent the lower pivot connections of the 55 adjacent side levers, a head strip and a closure foot board connecting the terminal levers of the tongs, a flexible top having the ends thereof secured to the head strip and to the foot board and the sides secured to the upper ends of the tongs, said flexible top limiting the extension of the tongs and forming in the extension thereof, a cot, a bench cover pivotally secured to the head strip and provided at the front with the 60 cross strip, said bench cover being designed to close down over the contracted tongs to form a seat and having the cross strip passing in front of the foot board and locking the folded tongs against extension, a gate 70 pivotally secured to the cross bar connecting the terminal pair of head levers and designed to close in, the head end of the extended cot and means carried by the head strip for releasably locking the gate closed, 75 as and for the purpose specified.

2. A combination bench and folding cot comprising lazy tong side members, a flexible top having the sides thereof connected to the upper ends of the lazy tongs and 80 forming in the extended position of the tongs, a cot, a hinged cover closing over the tongs in the collapsed position thereof and forming a bench, cross bars connecting the opposing pairs of tongs, and a permanent 85 foot closure member and a releasable head closure member carried by the tongs and arranged to inclose, in the collapsed position of the tongs, a storage compartment located between the flexible top and the 90 cross bars, as and for the purpose specified.

Signed at Winnipeg this 3rd day of December 1914.

HERBERT WATSON HOWELL.
